(57) **CLAIM**

The ornamental design for a decanter, as shown and described.

DESCRIPTION

FIG. 1 is a front perspective view of one embodiment of a decanter showing my new design;

FIG. 2 is a front view thereof;

FIG. 3 is a rear view thereof;

FIG. 4 is a left side view thereof, the right side view being a mirror image thereof;

FIG. 5 is a top view thereof; and,

FIG. 6 is a bottom view thereof.

The broken lines in the drawings depict portions of the decanter that form no part of the claimed design. Broken lines may show structure that is not part of the claimed design; but used to show environment in which the design is used. The views or portions of the decanter not illustrated form no part of the claimed design.
